ENGINE STARTING MECHANISM

Romeo M. Nardone, East Orange, N. J., assignor
to Eclipse Aviation Corporation, East Orange,
N. J., a corporation of New Jersey

Substituted for application Serial No. 726,159,
May 17, 1934. This application March 24, 1938,
Serial No. 197,971

2 Claims. (Cl. 123—179)

This invention relates to engaging and driving mechanism for rotary parts, and more particularly to a novel mechanism for starting an internal combustion engine.

5 An object of the invention is to provide a multiple ratio driving connection which will act automatically to take up the back-lash characteristic of certain driving mechanisms of the prior art when one member overruns the other.

0 The invention, although not confined to any particular type of starter, is particularly applicable to "inertia" starting devices, and the invention is shown in the accompanying drawings as embodied in an "inertia" starter of the de-
5 layed mesh type.

It is a known fact that a large amount of the energy developed in the driving motor, or stored in the flywheel (when the starter is of the "inertia" type) is lost in friction due to the slipping 0 of the clutch. The greater the mass to be accelerated, the greater is this loss. The starter begins to crank the engine at a speed of, say, 90 R. P. M. and since the engine cannot immediately assume this speed, a period of clutch slippage 5 occurs. Slippage ceases when the engaged engine and starter parts have reached the same speed. If the mass to be accelerated is large, slippage increases, reducing the speed of the flywheel and at the same time reducing the maximum speed of the engine. Accordingly, another object of the present invention is to reduce the amount of energy lost in clutch slippage, thereby increasing the efficiency of the starter. Other desirable features are also obtained as will be evident from an examination of the following specification and the accompanying drawings.

Only two embodiments of the present invention are shown in the accompanying drawings, but it is to be understood that the drawings are for the purpose of illustration only and are not designed as a definition of the limits of the invention, reference being had for this purpose to the appended claims.

Referring to the drawings,

5 Fig. 1 is a central longitudinal section of a device embodying the invention;

Fig. 2 is a transverse sectional view partly in elevation taken substantially along the lines 2—2 of Fig. 1;

Fig. 3 is a sectional view of a portion of a second embodiment of the invention; and

Figs. 4 to 9 are views of details of said second embodiment.

Referring to the drawings, there is disclosed a combined hand and power actuated starter of a

conventional type. As shown, the starter includes a flywheel 2 constituting an inertia element, and an engine engaging clutch element 3 which is movable into driving engagement with a corresponding clutch member 4 provided on or connecting with the crankshaft or crankshaft extension of the engine to be started. The mechanism is housed within a suitable casing constituted preferably by an inner section 5, intermediate sections 6 and 7, and a motor casing 8, the sections being removably secured together in any suitable manner, and the inner section 5 being provided with a flange 5a to receive bolts 9 for mounting the starter on a flange 10 of the engine crankcase.

The manually operable means for actuating the starter preferably takes the form of a cranking shaft rotatably mounted in intermediate housing section 7 with the outer end (not shown) projecting from said housing, and provided at its inner end with suitable means, such as a bevel pinion 11, for meshing engagement with a similar pinion 12 keyed to a shaft 13 constituting an integral extension of the closed end of a barrel 30 to be further described. The said shaft 13 is further provided with bushings on which are rotatably mounted two pinions 14, one being integral with internally toothed gear 15 adapted to mesh with gear teeth 16 formed near one end of a shaft 17, the said shaft 17 being adapted for operative connection, through novel means to be hereinafter described, with a stub shaft 20 to which the flywheel 2 is rigidly secured by suitable means, such as the key shown at 21. This stub shaft 20 is rotatably supported, as by ball bearings 22, in a suitable hub on a wall 23 extending across the section 7 of the starter casing. The shaft 17 is in turn rotatably supported at one end, by a bearing 26, in a boss 25 formed on casing section 6, and its opposite end is received in a bearing 27 mounted in transverse wall 23.

The gear 15 is provided centrally thereof with an integrally formed pinion 14, as above pointed out, and said pinion 14 constitutes the sun gear for a plurality of planetary gears 51, one of which is shown in section in the drawings, and one in elevation. These planetary gears 51, of which three are preferably employed, spaced at intervals of one hundred and twenty (120) degrees 50 about the sun gear 14, mesh with an internally toothed ring 52 which is rigidly secured in any suitable manner to the inner surface of housing section 5, such as by screws 52a. Each planetary gear is rotatably mounted, as by a bearing 53, on

a sleeve 54, the inner end of each sleeve being received in a spider or cage member having a hub integral with a second pinion 14 meshing with a second set of planets operatively connected with 5 barrel 30. Barrel 30 is preferably mounted on bearings, as shown at 56 and 57, the former being held in position by flange 58 of the barrel, and the latter by nut 59 and spring wire 61 clamped thereto, and also to the barrel as indicated at 62. 10 A retaining ring 66 carried by the outer ends of the screws 55 maintains bearings 53 in their proper positions on sleeves 54.

A multiple disc clutch is preferably provided in association with the barrel 30 to insure relative rotary movement between the engine engaging member and the train of gearing above described, whereby the latter is protected from damage due to an excessive shock or load. As shown, 15 the disc clutch comprises a plurality of inter- 20 leaving discs 79, alternately splined to the inner surface of the barrel 30 and the outer surface of a shell 80, internally threaded to engage a correspondingly threaded screw shaft 75, to be further described. Resilient means, such as a plurality 25 of coiled compression springs 81, the pressure of which is adjustable by a nut 82 threadedly engaging the end 83 of the barrel, are provided to press upon a flange 85 on member 80, and thus maintain the discs 79 in frictional engagement with 30 a pressure sufficient to insure transmission of torque from barrel 30 to shell 80, up to a predetermined capacity.

Fitted over the inner end of the starter is a cup-shaped member 89, that is preferably formed 35 of metal and is provided with a flange 91 adapted to be clamped between flange 5a of the starter housing, and the engine flange 10. The inner portion of member 89 is bent inwardly toward clutch member 3, as at 93, and is provided with a 40 central opening which is slightly larger in diameter than the outer diameter of the clutch member 3.

In order to prevent seepage of oil through the 45 central opening in member 89, the latter preferably carries a washer 94 of leather or equivalent material. Normally the inner portion of washer 94 is held in engagement with the adjacent surface of the head of clutch member 3 by means of a metallic washer 95 and a flange sleeve 97.

Rod 117 is axially movable through a central 50 bore in the screw shaft 75, preferably by means of the usual shifter fork as shown at 119 in Fig. 1, mounted on the usual transversely disposed shaft 121 oscillated by a suitable lever or bell crank as 55 indicated at 122, and corresponding to that shown at 55 in the Patent No. 1,786,118 granted to Raymond P. Lansing on December 23, 1930.

The rod is reduced in diameter as indicated at 60 124 to provide a shoulder abutting the end surface of the screw shaft 75, the rod being effective through the instrumentality of said shoulder to move the screw shaft axially until further motion is prevented by engagement of the stop nut 126 with the annular ledge 127 formed at the end of 65 the unthreaded portion of the inner surface of the shell 80. Axial movement of the screw shaft 75 is transmitted yieldably to the engine engaging member through the instrumentality of a coiled compression spring 128 which surrounds 70 the rod 117 and presses upon the washer 129 abutting the transverse portion 131 of the engine engaging member 3. A nut 132 provides means for adjusting the connection between the rod 117 and member 3.

Having now described the construction of a

conventional inertia starter of the character to which the present invention is well suited, there remains to be described the novel features of this invention.

Referring to the drawings, two different size 5 pinions 140 and 141 are secured to the flywheel. These mesh with different size gears 142 and 143. As best viewed on Fig. 2, gear 142 has internal cam shaped depressions 144 for overrunning clutch rollers 146. The inner race 147 is round 10 and is internally threaded for the reception of screw 148 having a long hub extension to movable cone clutch member 149 splined to shaft 17. Gear 143 is mounted by a frictionless bearing on the screw extension 148 and supports gear 142 by 15 means of a ball bearing. It has a cone face to fit cone 151. The latter is backed up by a spring 152 forcing the two cones together.

The flywheel is brought up to speed either by an electric motor 101 or by manual means. If by 20 hand, gear 15 drives pinion 16 which drives cone clutch 151. The latter being in engagement with gear 143, drives it and drive is transmitted to pinions 141 and 140. Pinion 140 drives gear 142 at a speed less than that of gear 143, thus overrunning. The centrifugal force on rollers 146 acts against gear 142 and offers no drag-resist- 25 ance.

When the flywheel is up to speed and the starter engaged to the engine, the drive is transmitted 30 from pinion 141 to gear 143 to cone clutch 151 and tends to crank the engine at high speed. However, the torque value of this cone clutch is such that it slips before the clutch 79 slips. After the starter is engaged, all gears tend to come 35 to rest. Therefore, as cone clutch slips, gear 142 will catch up and drive shaft 17 through the roller clutch 146, 147. Torque between 147 and 148 acts to move the latter to the right because of the thread and thus hold cone 151 away from gear 40 143. After the engine member 4 has been accelerated to a certain extent, the load on the starter diminishes sufficiently to cause the torque responsive member 148 to return to the left. Spring 152 now returns the cone clutch 151 into driving 45 position, and an increased cranking speed results.

The second period of slippage accelerates the 50 engine still further, but the total loss is less than would occur with a single reduction starter in bringing the engine up to equal speed. For the same engine speeds the flywheel can be reduced in size, or for equal flywheels and the same loss in energy, the engine can be accelerated to a higher speed.

In the modification shown in Figs. 3-9, the 55 lower speed gear 142 has a plurality of cam-surfaced recesses 161 at angularly spaced intervals, each containing a ball 162 and cooperating with correspondingly formed recesses 163 in a jaw clutch element 164 (shown in Fig. 9) having 60 teeth 165 engaging corresponding teeth 168 on the associated clutch element 166 (as viewed in Figs. 7 and 8) whose hub is splined to shaft 17, as shown at 167. On the remote side of clutch element 166 are one or more projections 169 65 (Fig. 6) mating with grooves 170 in an inertia disc 171 (shown in Figs. 4 and 5) which is free to rotate on shaft 17 and abuts an axially fixed clutch thrust bearing 26. Cone clutch element 149 has a marginal flange 173 locking it to clutch 70 member 164, and it faces in a direction opposite to that of Fig. 1 to engage the gear 143, the bearing 174 taking the thrust of engaging spring 152. A second spring 175 is provided to tend to hold 75 clutch element 166 out of engagement with clutch

element 164, and a stop washer 176 restrains the outer end of spring 152.

The operation of the starter of Fig. 1, when revised to include the structure of Fig. 3 in lieu of the corresponding elements of Fig. 1, is as follows:

After the flywheel 2 has been accelerated (by either of the means previously described) to the desired speed, and the members 3 and 4 meshed, 10 the cone clutch 143, 149 slips under the load thus imposed. This slipping permits shaft 17, and the parts splined thereto, to decelerate, whereupon inertia disc 171 runs ahead of clutch element 166, camming the latter into mesh with 15 clutch element 164. Gear 142 now takes up the drive, and in doing so it cams balls 162 to the left and causes a corresponding leftward movement of clutch elements 164 and 149, whereby the former is more firmly meshed with the driven 20 clutch element 166, while the cone clutch elements 143 and 149 are separated. The resulting drive through parts 166, 17 et seq., accelerates the engine to a certain extent, or until the load diminishes sufficiently to enable spring 152 to 25 engage cone clutch 143, 149; the balls 162 at the same time receding in recesses 161 and 163, and thereby enabling spring 175 to again disengage clutch teeth 168, 165, and hold said clutch teeth disengaged while the drive to the engine proceeds 30 through elements 141, 143, 149 and 17 until the "starting" of the engine is completed, unless the load again becomes excessive, in which event the cycle is repeated.

An important feature of this invention is the 35 following:

An engine may fire once or twice, and then cease firing. As it fires, it will tend to run ahead of the starter. However, since the normal starter cannot follow up, all the energy imparted to the 40 engine by the explosion is lost and it has to decrease its speed enough to allow the starter to catch up. With the present invention, when firing occurs and the engine speeds ahead, the high speed cranking gears will immediately go in 45 action and cranking speed will be increased. This will cause the starter to keep pace with the engine as it fires while permitting the low speed gears to do the actual cranking.

This application is a substitute for my application Serial No. 726,159 filed May 17, 1934.

What is claimed is:

1. In an engine starter of the inertia type, the combination with high and low speed shafts, of a high speed fly wheel mounted on said high speed shaft, accelerating means for said fly wheel, said accelerating means including a friction clutch operatively connected with said low speed shaft and having a toothed member forming a part thereof, a pinion on said high speed shaft meshing with said toothed member, a one-way clutch operatively connected with the low speed shaft and including a toothed member, a second pinion on said high speed shaft meshing with the toothed member of said one-way clutch, the ratio of the first named pinion and toothed member and the ratio of the second named pinion and toothed member being such that the one-way clutch overruns while said accelerating means operates to accelerate the fly wheel through the first named clutch.

2. In an engine starter of the inertia type, the combination with high and low speed shafts, of a high speed fly wheel mounted on said high speed shaft, accelerating means for said fly wheel, said accelerating means including a friction clutch operatively connected with said low speed shaft and having a toothed member forming a part thereof, a pinion on said high speed shaft meshing with said toothed member, a one-way clutch operatively connected with the low speed shaft and including a toothed member, a second pinion on said high speed shaft meshing with the toothed member of said one-way clutch, the ratio of the first named pinion and toothed member and the ratio of the second named pinion and toothed member being such that the one-way clutch overruns while said accelerating means operates to accelerate the fly wheel through the first named clutch, means for meshing the starter with an engine member to crank the latter, and means effective upon a predetermined slippage in said friction clutch during operation of the starter to crank the engine member, to render the one-way clutch operative to transmit torque from the fly wheel to the low speed shaft.

ROMEON M. NARDONE.
